UNITED STATES PATENT OFFICE.

EDWARD C. MEIER, OF PHOENIXVILLE, PENNSYLVANIA.

SUPERHEATER FOR BOILERS.

1,244,530.

Specification of Letters Patent. Patented Oct. 30, 1917.

Application filed March 3, 1917. Serial No. 152,179.

To all whom it may concern:

Be it known that I, EDWARD C. MEIER, a citizen of the United States, residing at Phoenixville, in the county of Chester and State of Pennsylvania, have invented certain new and useful Improvements in Superheaters for Boilers, of which the following is a specification.

My invention consists of an improved superheater structure for boilers.

In various types of boilers employing superheaters, the water tubes, drums, and other elements which contain water to be converted into steam, are heated by the hot gases and other products of combustion before the latter come in contact with the superheater. In these constructions it is obvious that a great part of the heat is absorbed before reaching the superheater.

For certain purposes where an exceptionally high temperature and pressure of superheated steam is not necessary, boilers of said types are practical. However, where it is necessary to secure and maintain superheated steam under high temperature and pressure, such for example as for use in connection with turbines, boilers of the above mentioned type have been found inefficient for the reason that in order to secure sufficient heat for the superheater, it is necessary to constantly force the furnace to its fullest capacity and in some instances where superheated steam at extremely high temperature and pressure is required, boilers of said type are entirely inadequate.

One object of my invention is to provide a boiler with a superheater structure which is made in such manner that the hot gases and products of combustion will engage the tubes, or other conduits for the steam to be superheated, prior to their passage to the water tubes or other elements which contain water to be converted into steam.

Another object is to provide a superheater housing which will act to prevent the deposit of the heavier particles of fuel in combustion, on the tubes or other portion of the superheater proper.

A further object is to so construct said housing and other portion of the boiler that the hot gases will be caused to circulate through the superheater housing.

Another object is to provide means for regulating the amount of the products of combustion which circulate through the su-

perheater housing and thereby regulate the degree of temperature and pressure of the superheated steam.

A still further object is to make my invention of simple construction and so that it can be quickly and easily installed and cleaned.

These objects, and other advantageous ends which will be described hereinafter, I attain in the following manner, reference being had to the accompanying drawings in which—

Figure 1 is a longitudinal sectional elevation of a boiler including my improved superheater structure.

Fig. 2 is a sectional elevation taken on the line 2—2 of Fig. 1 and drawn on an enlarged scale.

Fig. 3 is a sectional plan view taken on the line 3—3 of Fig. 1 and drawn on an enlarged scale.

Fig. 4 is a section on the line 4—4 of Fig. 3.

Fig. 5 is a view of the same general nature as shown in Fig. 1 but showing my invention applied to what is known as a "Three pass boiler" in which the flues from the superheater housing extend at an angle and open into space within one of the passes and between two of the longitudinally extending baffles for a purpose hereinafter fully described.

Fig. 6 is a view of the same general type of boiler shown in Fig. 1, but in which certain of the elements relating to the superheating structure are differently positioned from that shown in Fig. 1.

Fig. 7 is a fragmentary elevation on a reduced scale showing a modified form in the construction of one of the superheater flues.

Referring to Figs. 1 to 4 inclusive, 1 represents a supporting structure which may be of brick and which forms a support for the water legs 2 and 3 of a boiler having water tubes 4 which communicate with the water legs 2 and 3 and are arranged at a slight incline from the horizontal.

The supporting structure 1 forms the enclosure for the boiler in which are located the grate bars 5, said grate bars at their rear end terminating in a wall 6 which leads transversely across the enclosure and extends to a height a short distance above the upper level of the grate bars 5.

The wall 6 serves to divide the interior of

the inclosure into two compartments 7 and 8. The compartment 7 forms the fire box, while the compartment 8 forms what is known as the combustion chamber, the tubes 4 extending from front to back across both the fire box 7 and the combustion chamber 8.

10 The water legs 2 and 3 at their uppermost portions communicate with the drum 9, the latter being operative as a container for the steam generated.

15 The supporting structure 1 at its uppermost portion provides a flue 10, said flue serving to take off the products of combustion after they have performed their function of converting the water within the tubes 4 into steam and superheating the steam in a manner hereinafter more fully described.

20 Baffles 11 and 12 are formed on and between certain of the tubes 4, and these baffles may be made up of a series of tile positioned and constructed for example as shown and described in my prior United 25 States Patent No. 1,188,967 dated June 27, 1916.

25 The baffle 11 is positioned on the lower tubes 4 and extend from the front water leg 2 rearwardly, stopping short of the water leg 3, so that to provide a passage through which the products of combustion from the combustion chamber 8 can enter between the tubes 4.

30 The baffle 12, on the other hand, extends forwardly from the rear water jacket 3 and stops short of the front water leg 2 and is positioned adjacent the uppermost tubes 4, thus compelling the products of combustion to pass between the tubes 4 throughout their entire length prior to its entering into the chamber 13 which is formed between the baffle 12 and the upper or top covering 14.

35 The products of combustion after passing through the passage 12 eventually pass outwardly through the flue 10 to the chimney and atmosphere.

40 In carrying out my invention, I provide two partitions 15 and 16, said partitions being spaced from the side walls 17 and 18 of the supporting structure 1. These partitions extend from the wall 6 rearwardly and intersect the rear wall 19 of said supporting structure. Covers 20 and 21 are 45 preferably made of porous fire brick and extend from the partitions 15 and 16 respectively to the side walls 17 and 18 and thus provide chambers 22 and 23, it being noted that said covers also extend from the wall 50 6 to the wall 19.

55 By this construction, a central chamber 24 is formed between the partitions 15 and 16, this chamber being open at its top and directly communicating with the uppermost 60 part of the combustion chamber 8, it being

noted that said partitions 15 and 16 and the covers 20 and 21 are located in the combustion chamber 8.

65 Inlet ports or openings 25 and 26 are provided in the partitions 15 and 16 and communicate with the central chamber 24 and with the chambers 22 and 23. I also provide side flues 27 and 28 within the walls 70 17 and 18, and these flues at their bottom portions communicate with the chambers 22 and 23 respectively. At their upper ends, the flues 27 and 28 communicate with the spaces between the tubes 4 and between the baffles 11 and 12.

75 Superheaters 29 and 30 have their heads 80 31 mounted within the rear wall 19, and their tubes 32 project into the chamber 22 and 23 respectively. The forward end of said superheater tubes rest on pedestals 33 which are located within the chambers 22 85 and 23.

90 As illustrated in Figs. 1 to 4, inclusive, the tubes 32 of the superheater extend forwardly and stop short of the inlet ports 25 and 26, it being noted that said inlet ports are formed in the extreme forward end of the partitions and that the flues 27 and 28 intersect the chambers 22 and 23 at the extreme rear end thereof.

95 Dampers 34 are pivotally mounted within the upper ends of the flues 27 and 28 and have rods 35 which extend beyond the outer surface of the rear wall 19. The superheaters 30 connect with the drum 9 and receive their steam therefrom through the medium of a pipe 36, said pipe being broken away in Fig. 1 of the drawing, but it will be noted that this pipe connects with the inlet passages 37 of the superheater, said superheater being provided with outlet pipes 100 38 for conducting the superheated steam.

105 A doorway 39 is formed in the rear wall 19 and communicates with the lower portion of the central chamber 24. This doorway permits the ready cleaning of the central chamber 24.

110 My invention operates as follows:

115 The hot gases and products of combustion arising from the grate 5, pass over the top of the wall 6. A portion of these gases pass rearwardly over the covers 20 and 21 and central chamber 24, and then upwardly between the tubes 4 and baffles 11 and 12, and then through the opening provided between the forward end of the baffle 11 and 120 the water leg 2 to the chamber 13 and flue 10. This movement of the gases produces a suction through the side flues 27 and 28, and causes a portion of the hot gases to pass downwardly into the central chamber 24 125 and then through the inlet ports 25 and 26 into the chambers 22 and 23, then through the flues 27 and 28 into the space between the tubes 4 and the baffles 11 and 12.

130 The portion of gas which thus passes

through the chambers 22 and 23 is exceptionally hot, since it comes direct from the fire box 7 over the wall 6. The superheater tubes within said chambers 22 and 23 are therefore heated to a very high temperature, thus heating the steam therein to an extremely high degree.

By providing the chambers 22 and 23 with the partitions 15 and 16 and the covers 20 and 21, they are protected against the deposit of dirt, since only the lighter particles of the products of combustion will pass through the inlet ports 25 and 26, the heavier dirt collecting on the tops of the covers 20 and 21, and at the bottom of the central chamber 24.

The chamber 24 can be readily cleaned through the doorway 39, and the dirt on the covers 20 and 21 can be readily scraped therefrom through the medium of the firing door 40 which is formed in the front wall 41 of the supporting structure. Also, by making the covers 20 and 21 of a porous fire brick, heat will penetrate them to the exclusion of the dirt and will thereby tend to more efficiently heat the superheater tubes.

By the adjustment of the dampers 34, the amount of the gases circulating through the chambers 22 and 23 can be regulated to suit various requirements as to the degree and pressure of the superheated steam, since it will be noted that said dampers when moved will vary the amount of opening in the flues 27 and 28.

In Fig. 5, I have shown my invention in connection with what is known as a "Three pass boiler" including three baffles 42, 43, and 44. In this construction I have shown one of the side wall flues, indicated at 45 extending at an angle or incline and communicating with the rear of the superheating chamber and opening directly into the space between the baffles 43 and 44. In all other respects the construction shown in Fig. 5 is substantially identical to that described in connection with Figs. 1 to 4 inclusive, and I have therefore given similar parts corresponding reference numerals.

In Fig. 6, I have illustrated my invention in connection with a two pass boiler of the type shown in Fig. 1, but instead of having the inlet ports opening into the forward ends of the superheater chamber, I have shown them entering the rear, one of said inlet ports being indicated by the reference numeral 46. In this instance, I form the side wall flue, indicated at 47, so that it intersects the forward part of the superheater chamber and also directly opens into the space between the upper baffle 48 and the lower baffle 49.

In all other respects the elements illustrated in Fig. 6 are substantially similar to those previously described in connection

with Figs. 1 to 4 inclusive, and I have therefore given similar parts corresponding reference numerals.

In my present invention, the superheater receives direct heat from the fire box, while the same is at a high temperature. This portion of the products of combustion, after heating the superheater tubes, passes between the tubes of the boiler proper and thereby acts to heat the latter in combination with the gases which pass directly from the fire box to the boiler tubes, thus the products of combustion passing through the superheater chambers perform another function in that it assists in generating steam due to its passage through the boiler tubes prior to passing off through the chimney.

It is well known that if tubes become coated with deposit of dirt, that they soon burn out. Therefore, my present invention is valuable in that it protects the tubes from dirt and also permits them to be heated by the products of combustion directly from the fire box.

It will be noted that in the several views of drawing, I have shown a well known type of superheater including the head 31 and the tubes 32, however, it will be understood that any form of superheater can be used in which the tubes can be extended into the chambers 22 and 23.

Cleaning passages 50 are formed through the rear wall and on a level with the floor of the superheating chambers 22 and 23. These passages permit the removal of any dust which collects on the floor of the superheating chambers and are preferably closed at their outer ends by doors 51.

Fire brick doors 52 and 53 are located within the central chamber 24 and are slideable by rods 54 and 55 respectively which pass through the rear wall. These fire brick doors can be moved into position to close the inlet ports or openings 25 and 26 if it is desired to cut off the superheating chambers 22 and 23 from the products of combustion. For example, if it is desired to remove the superheaters, it is only necessary to close the doors 52 and 53 and the superheaters may be bodily removed, it being noted that the dampers 34 can also be closed, thus permitting the removal of the superheaters without interfering with the operation of the other portions of the boiler.

It will be further noted that with my invention it is an extremely easy matter to remove the entire superheaters since they may be pulled out of the rear wall and being at a low level, they may be readily repaired and replaced.

In the form of my invention shown in Fig. 7, instead of having the outlet flues extending at an angle upwardly such as shown in Fig. 5, I form the flue substantially vertical

for a portion of its length, such for example as shown at 56 and then continue the flue forwardly in a substantially horizontal direction as shown at 57. By this construction, 5 which is less expensive than the angular construction shown in Fig. 5, I can secure the same altitude for the outlet end of the flue within the pass between the baffles so as to get the desirable suction through the flue. 10 In all other respects the construction of Fig. 7 is similar to that described in connection with Fig. 5, and I have therefore given similar parts like reference numerals.

One of the important features of my invention 15 is the formation of the flues in connection with the outlets of the superheater chambers and to locate the dampers 34 within the flues where they do not receive the direct heat from the furnace. By this construction I can use comparatively thin dampers without fear of their being readily 20 burned out. Fig. 2 of the drawing shows these dampers located at the extreme upper ends of the flues 27 and 28, and the hot 25 products of combustion are therefore compelled to pass entirely through the superheating chambers and flues prior to their engagement with the dampers. This renders my invention extremely practical since 30 in various types of boilers, dampers have always been troublesome in view of the fact that they readily burn out and in order to prevent their burning out, it was customary to make them of heavy fire brick.

35 While I have described two superheaters and two covered chambers, it will be noted that if desired only one of the covered chambers can be used or more than two covered chambers can be used, however, in each 40 instance I prefer to form the inlet opening in the partition which provides the covered chamber.

While I have described my invention as taking a particular form, it will be understood 45 that the various parts of my invention may be changed without departing from the spirit thereof, and hence I do not limit myself to the precise construction set forth, but consider that I am at liberty to 50 make such changes and alterations as fairly come within the scope of the appended claims.

Having thus described my invention, what I claim as new and desire to secure by Letters Patent is:

55 1. The combination with a boiler, of a superheater construction including means providing an elongated horizontally extending chamber arranged below the steam-generating elements of the boiler and substantially on a level with the fire box thereof, said means including a side wall having an inlet opening for laterally admitting products of combustion into said chamber, said 60 means also having an outlet opening for said

products of combustion leading from said chamber, and a superheater extending within said chamber, substantially as described.

2. The combination with a boiler, of a superheater construction including means 70 providing an elongated horizontally extending chamber arranged below the steam-generating elements of the boiler and substantially on a level with the fire box thereof, said means including a side wall having an 75 inlet opening for laterally admitting products of combustion into said chamber, said means also having an outlet opening for said products of combustion leading from said chamber, a superheater extending with- 80 in said chamber, and means providing a chamber alongside of said superheater chamber and with which said inlet opening communicates, said second chamber serving as a conducting passage for the products of 85 combustion prior to their entering the superheater chamber, substantially as described.

3. The combination with a water tube boiler, of means providing a superheater chamber arranged below the water tubes and 90 substantially on a level with the fire box of the boiler, said means including a side wall having an inlet opening for laterally admitting the products of combustion into said chamber, and baffles interposed between the 95 tubes of the boiler and extending longitudinally thereof, said first means providing an outlet flue for the products of combustion from said superheater chamber, said flue having its outlet opening between said baf- 100 fles, substantially as described.

4. The combination in a boiler, of a fire box, a combustion chamber adjacent thereto, a partition in said combustion chamber and spaced from a side wall thereof, a cover extending from the partition to the side wall and providing a superheater chamber, said partition having an opening therein for permitting the products of combustion to enter the superheater chamber from the side, 110 means providing an outlet opening for the superheater chamber and a superheater extending within said superheater chamber, substantially as described.

5. The combination in a boiler, of a sup- 115 porting structure including front, side, and rear walls, a fire box formed at one end of said structure, a combustion chamber formed in the opposite end of said structure, a wall extending transversely between the fire box 120 and the combustion chamber, a partition extending from said latter mentioned wall to the rear wall of the supporting structure, said partition extending substantially parallel with one of said side walls and di- 125 viding the lower portion of the combustion chamber, a cover extending from said partition to one of said side walls and with the partition forming a superheater chamber, said partition having an opening therein for 130

permitting entrance of the products of combustion from said combustion chamber into the side of said superheater chamber, means forming an outlet for said superheater chamber, and a superheater extending within said latter mentioned chamber, substantially as described.

6. The combination in a water tube boiler, of a supporting structure including front 10 side, and rear walls, a fire box formed at one end of said structure, a combustion chamber formed in the opposite end of said structure, a wall extending transversely between the fire box and the combustion chamber, a 15 partition extending from said latter mentioned wall to the rear wall of the supporting structure, said partition extending substantially parallel with one of said side walls and dividing the lower portion of the combustion chamber, a cover extending from said partition to one of said side walls and, with the partition, forming a superheater chamber, said partition having an opening therein for permitting entrance of the 20 products of combustion from said combustion chamber into the side of said superheater chamber, means forming an outlet for said superheater chamber, a superheater extending within said latter mentioned 25 chamber, means forming a flue of comparatively small cross section, said flue extending from the outlet opening of said superheater chamber and opening into the space between the water tubes, substantially as 30 described.

7. The combination in a water tube boiler, of a supporting structure including front, side, and rear walls, a fire box formed in said structure, a combustion chamber adjacent 35 said fire box, a wall extending transversely between the fire box and the combustion chamber, a partition extending from said transversely extending wall to the rear wall of the supporting structure, said partition dividing the lower portion of the combustion chamber, a cover extending from said partition to one of said side walls and with the partition forming a superheating 40 chamber, said partition having an opening therein for permitting entrance of the products of combustion from said combustion chamber into the side of said superheater chamber, water tubes arranged above 45 said fire box and combustion chamber, two superimposed baffles interposed between the water tubes and extending longitudinally thereto to form a passage for the products of combustion from said fire box, a superheater extending within said superheater 50 chamber, means providing an outlet opening communicating with said superheater chamber, and a flue extending from said outlet passage and having its entire outlet end leading into the space between said baffles, substantially as described.

8. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, and flues communicating with said covered chambers and opening into the space between said water tubes, substantially as described.

9. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, and flues communicating with said covered chambers and opening into the space between said water tubes and between said baffles, substantially as described.

10. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers.

chamber and the covered chambers, water tubes mounted above said combustion chamber, baffles spaced apart and arranged adjacent said water tubes, superheaters extending within said covered chambers, flues communicating with said covered chambers and opening into the space between said water tubes, and dampers for regulating the passage of the products of combustion through 10 said covered chambers, substantially as described.

11. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partitions to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, flues communicating with said covered chambers and opening into the space between said water tubes, and dampers interposed within said flues for regulating the passage of the products of combustion through said covered chambers, substantially as described.

12. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, and flues formed in said side walls and communicating with said covered chambers and opening into the space between said water tubes, substantially as described.

13. The combination in a boiler, of a supporting structure including front, side, and

rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, flues communicating with said covered chambers and opening into the space between said water tubes, and a doorway formed in said rear wall and communicating with the bottom of said central chamber, substantially as described.

14. The combination in a boiler, of a supporting structure including front, side, and rear walls, a fire box formed in said structure, a combustion chamber adjacent said fire box, a wall extending transversely between the fire box and the combustion chamber, two partitions spaced from the side walls and extending between said transverse wall and the rear wall, covers extending from said partition to said side walls and thereby forming covered chambers, said partitions being spaced apart to form a central chamber which is open at its top and communicating with the combustion chamber, inlet openings in said partitions and communicating respectively with the central chamber and the covered chambers, water tubes mounted above said combustion chamber, baffles spaced apart and arranged adjacent said water tubes, superheaters extending within said covered chambers, and flues formed in said side walls and communicating with said covered chambers and opening into the space between said water tubes and between the baffles, substantially as described.

15. A superheater inclosure for steam boilers including a wall forming a partition adjacent the combustion chamber of the boiler, said partition including an opening for laterally admitting the products of combustion into the chamber provided by the inclosure, and a door for closing said opening, substantially as described.

16. A superheater inclosure for steam boilers including a wall forming a partition adjacent the combustion chamber of the boiler, said partition including an opening for laterally admitting the products of combustion into the chamber provided by the in-

closure, and a door slidably mounted adjacent said opening and adapted to regulate the amount of products of combustion entering said compartment, substantially as described.

17. The combination in a boiler, of means providing a combustion chamber, baffles located above said combustion chamber and spaced apart to provide a passage for the products of combustion, means providing a superheater chamber, an inlet opening in said superheater chamber communicating with the combustion chamber, and an outlet flue leading directly from the superheater chamber and having its entire outlet end opening into the space between said baffles at a point within the length thereof, substantially as described.

18. The combination in a boiler, of means providing a combustion chamber, baffles located above said combustion chamber and spaced apart to provide a passage for the products of combustion, means providing a superheater chamber, an inlet opening in said superheater chamber communicating with the combustion chamber, an outlet flue leading directly from the superheater chamber and having its entire outlet end opening into the space between said baffles at a point within the length thereof, and a damper in said flue located in a position remote from said superheater chamber, substantially as described.

19. The combination in a boiler, of means providing a combustion chamber, baffles located above said combustion chamber and spaced apart to provide a passage for the products of combustion, means providing a superheater chamber, an inlet opening in said superheater chamber communicating with the combustion chamber, and an outlet flue leading directly from the superheater chamber and extending upwardly, said flue having its entire outlet end opening into the

space between the baffles at a point within the length thereof, and a damper located adjacent the upper end of said flue, substantially as described.

20. The combination in a boiler, of a supporting structure, a fire box, a combustion chamber directly adjacent the fire box, a partition in said combustion chamber dividing the lower part thereof, a cover extending from said partition to a side wall of the supporting structure to form a superheater chamber, said partition having a side opening therein to admit products of combustion laterally into the superheater chamber, means providing an outlet opening for said superheater chamber, a door for closing said first opening, and a superheater extending into said latter chamber, substantially as described.

21. The combination in a boiler, of a supporting structure, a fire box, a combustion chamber directly adjacent the fire box, a partition in said combustion chamber dividing the lower part thereof, a cover extending from said partition to a side wall of the supporting structure to form a superheater chamber, said partition having a side opening therein to admit products of combustion laterally into the superheater chamber, means providing an outlet opening for said superheater chamber, a superheater extending into said latter chamber, means providing a dust cleaning passage communicating with the superheater chamber, and a door for closing said passage, substantially as described.

In testimony whereof I have signed my name to this specification in the presence of two subscribing witnesses.

EDWARD C. MEIER.

Witnesses,

F. H. MEIER,
N. JOHN NELSON.
